FILLER DEVICE FOR SHOES

Axel Arnold Lawson, Beverly, Mass., assignor to
United Shoe Machinery Corporation, Paterson,
N. J., a corporation of New Jersey

Application August 16, 1932, Serial No. 629,031
In Great Britain February 11, 1932

9 Claims. (Cl. 12—124)

This invention relates to improvements in devices adapted to be inserted in boots and shoes to facilitate the performance of operations upon them. Although not necessarily limited thereto the invention is herein set forth by way of illustration with particular reference to the rounding and channeling of the soles of shoes of the McKay type in process of being repaired.

Rounding and channeling machines as usually constructed are provided with work guiding means in the form of a crease guide arranged to enter and ride along a welt crease. In a shoe of the McKay type, however, there is not, until the outsole has been permanently attached to the upper, any well-defined or definite crease between the upper and the outsole with which the crease guide of a rounding and channeling machine may cooperate to guide the shoe.

In repairing a welt shoe it has not been customary to employ a last or filler, the materials adjacent to the welt crease being relied upon to cooperate satisfactorily with the crease guide of the rounding and channeling machine without being supported otherwise than by the insole and the inseam stitches. In cases, however, where the insole is thin or has been considerably worn, it is liable to turn up at the edge or to buckle under the pressure of the work guide and in such an event the work will not be properly guided and the outsole will not be rounded or channeled accurately.

In view of these conditions, one object of the present invention is to provide a device which may be sold at a relatively small price and which will enable a shoe repairer to perform rounding or channeling operations, for example, with facility on any work that may be brought to him, without requiring him to provide himself with a stock of lasts of the usual run of sizes and styles.

To the accomplishment of this object, the invention provides an improved device of the type shown in United States Letters Patent No. 1,733,205, granted October 29, 1929, on the application of Ricks & Wilson, and therein termed a "filler". The illustrated filler has two form members of thickness merely sufficient to support the shoe upper adjacent to the insole but separable to adjust the filler to different shoes, thus rendering the supporting action of the filler very positive and definite. Preferably, also, and to the same end, these form members are self-adjustably mounted on the expandable frame of the filler. Advantageously, also, the illustrated filler is provided with a resilient member contacting

with the shoe upper to hold the filler down with its form members in contact with the insole.

These and other features of the invention comprising certain combinations and arrangements of parts will be apparent from the following description of a preferred embodiment of the invention shown in the drawing, in which

Fig. 1 is a perspective view;

Fig. 2 is a cross-section on the line II—II of Fig. 1; and

Fig. 3 is a cross-section on the line III—III of Fig. 1.

The illustrated form comprises a U-shaped frame having two arms 12, 14 hinged to each other at 16. The forms are preferably made in rights and lefts, and the arm 12 lies on the inside. The main body of the arm 12 is formed as a substantially straight rod, while the arm 14 has an inwardly extending ear 18 which supports an upstanding pin 20.

A cam 22 is slidably mounted on the inner arm 12, and has a rib 24 diverging from the longitudinal axis of the arm 12 and engaging between the pin 20 and a downwardly projecting flange 25 mounted on the pin. Adjustment of the cam 22 by means of a thumb piece 26 thus opens and closes the arms 12, 14 fanwise. The angle of divergence of the rib 24 from the axis of the arm 12 is small enough so that the friction of the parts will prevent the sliding of the cam under lateral compression of the device. The device is thus self locking in laterally expanded position.

Each of the arms 12, 14 carries at its front end a block 28 pivoted to it on a vertical axis 30, and each of these blocks has pivoted to it a form member 32 or 34, on a transverse horizontal axis 36. Each of the blocks 28 is formed with an upstanding lug 37 at its front end which loosely overlaps the end of the arm 12 (or 14) and thus limits its movement about the axis 30. The lower face of the block serves as a stop to limit the movement of the attached form member about the axis 36. The form members 32, 34 are formed as plates having only the thickness requisite to support the upper of a shoe at the portion directly adjacent the sole.

An adjustable heel piece 38 is provided comprising a straight horizontal rod with an upstanding rear end 40. The rod is freely slideable to the rear through a lug 42 mounted on the arm 12, but is held against forward sliding by a Horton clutch device 44. When the heel piece is set the device is thus held against longitudinal compressive stresses.

A shoe upper contacting member 48 is pivotally

mounted on the pin 20 and has a swinging movement on the pin limited by the flange members 50. This member 48 is U-shaped and is formed of resilient material. Its purpose is to contact 5 with the upper part of the shoe in order to force the body of the device down on the insole of the shoe and thus enable the form members 32, 34, the outer edges of which are shaped approximately to the outline of the inside and outside fore-part edges of a shoe, to support the upper adequately at these places.

In use the device is placed in a shoe, and pushed forward until the form members 32, 34 and the 15 spring member 48 are in the proper position longitudinally of the shoe. The device is then expanded by pulling the cam 22 backward until the form members are properly laterally positioned against the periphery of the upper and then the heel piece 38 is pulled back to contact 20 with the counter portion of the shoe, thus holding the device against displacement in the shoe.

Having described my invention, what I claim as new and desire to secure by Letters Patent of the United States is:

25 1. A filler for use in repairing shoes having two forepart form members of thickness merely sufficient to support a shoe upper adjacent to the insole, the form members being separable to adjust the filler to different shoes, and a resilient means 30 mounted on the filler to hold the form members in contact with the sole by pressure against the upper.

35 2. A shoe filler having a laterally expandable frame, and two form members mounted thereon having their outer peripheries shaped respectively to conform approximately to the inner and outer peripheral contours of an insole forepart, the peripheral vertical thickness of the form members being sufficient, merely, to support the 40 shoe upper along its periphery adjacent to the insole, and means for laterally expanding the frame.

45 3. A filler for use in repairing shoes having a laterally expandable frame, and two form members pivotally mounted, thereon having their outer peripheries shaped respectively to conform approximately to the inner and outer peripheral contours of an insole forepart, the peripheral vertical thickness of the form members being 50 sufficient, merely, to support the shoe upper along its periphery adjacent to the insole, and means for laterally expanding the frame.

55 4. A filler for use with a channeling or rounding machine having two longitudinally extending frame members pivotally connected at their rear ends, a cam member mounted on one of the frame members and cooperating with the other to expand the frame, and two form members mounted one on the front end of each of the frame members, said form members having their outer peripheries shaped respectively to conform approximately to the inner and outer peripheral contours of an insole forepart, the peripheral vertical thickness of the form members being sufficient, merely, 60 to support the shoe upper along its periphery adjacent to the insole.

65 5. A filler for use in repairing shoes having two longitudinally extending frame members pivotally connected at their rear ends, a cam member mounted to slide along one of the frame members

and having a rib formed at an acute angle to the direction in which it slides, a flange on the other frame member cooperating with the rib to expand and contract the frame, a form member mounted on the front end of each frame member and pivoted thereto on vertical and laterally extending horizontal axes, said form members having their outer peripheries shaped respectively to conform approximately to the inner and outer peripheral contours of an insole forepart, the peripheral vertical thickness of the form members being sufficient, merely, to support the shoe upper along its periphery adjacent to the insole.

6. A filler for use in repairing shoes having a laterally expandable frame, and two form members mounted thereon having their outer peripheries shaped respectively to conform approximately to the inner and outer peripheral contours of an insole forepart, the peripheral vertical thickness of the form members being sufficient, 20 merely, to support the shoe upper along its periphery adjacent to the insole, means for laterally expanding the frame, and a resilient pressure member extending between the frame and the shoe upper to hold the form members in contact 25 with the insole.

7. A filler for use with a channeling or rounding machine having a laterally expandable frame, and two form members mounted thereon having their outer peripheries shaped respectively to conform approximately to the inner and outer peripheral contours of an insole forepart, the peripheral vertical thickness of the form members being sufficient, merely, to support the shoe upper along its periphery adjacent to the insole, 30 means for laterally expanding the frame, and an adjustable heel member mounted on the frame to hold the filler against rearward sliding in the shoe.

8. A filler for use with a channeling or rounding machine having two longitudinally extending frame members pivotally connected at their rear ends, a cam member mounted on one of the frame members and cooperating with the other to expand the frame, two form members mounted 45 one on the front end of each of the frame members, said form members having their outer peripheries shaped respectively to conform approximately to the inner and outer peripheral contours of an insole forepart, to support the 50 shoe upper along its periphery adjacent to the insole, and a resilient pressure member extending between the frame and the shoe upper to hold the form members in contact with the insole.

9. A filler for use with a channeling or rounding machine having two longitudinally extending frame members pivotally connected at their rear ends, a cam member mounted on one of the frame members and cooperating with the other to expand the frame, two form members mounted one 60 on the front end of each of the frame members, said form members having their outer peripheries shaped respectively to conform approximately to the inner and outer peripheral contours of an insole forepart, to support the shoe 65 upper along its periphery adjacent to the insole, and an adjustable heel member mounted on the frame to hold the filler against rearward sliding in the shoe.
